UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

COILING MACHINE.

Application filed February 23, 1921. Serial No. 447,149.

To all whom it may concern:

Be it known that I, JOHN F. O'CONNOR, a citizen of the United States, residing at Chicago, in the county of Cook and State of Illinois, have invented a certain new and useful Improvement in Coiling Machines, of which the following is a full, clear, concise, and exact description, reference being had to the accompanying drawings, forming a part of this specification.

This invention relates to improvements in coiling machines.

One object of the invention is to provide an efficient, heavy duty machine, adapted for the coiling of rods or bars and more especially adapted for the coiling of rods or bars into high capacity springs such as are used in shock absorbing mechanisms of railway draft riggings.

A more specific object of the invention is to provide a coiling machine of the general character above indicated wherein provision is made for adjustment for different pitch, different diameter coils, and different diameter materials used.

One specific object of the invention is to provide a novel guide to insure proper deflection and bending of the rod or bar material during the coiling process as it passes between certain of the bending rollers and to prevent possible jamming of the material especially when the front end of the rod or bar passes from one roller to another.

Other objects of the invention will more clearly appear from the description and claims hereinafter following.

In the drawings forming a part of this specification, Figure 1 is a side elevational view of a coiling machine embodying my improvements. Fig. 2 is an end view of the machine illustrated in Fig. 1 and illustrating also a partially coiled rod. Fig. 3 is a sectional view corresponding substantially to the section line 3-3 of Fig. 2. Fig. 4 is a plan view of one of the coiling or bending rollers showing more particularly the means for positively rotating the same. Fig. 5 is a sectional view corresponding substantially to the section line 5-5 of Fig. 2. Figure 6 is a vertical, sectional view corresponding substantially to the section line 6-6 of Fig. 1. Fig. 7 is an enlarged detail sectional view taken in a general transverse direction of the mandrel in substantially a plane coinciding with the pitch of the coil

being formed and illustrating more particularly my improved guide. Fig. 8 is a perspective view of the improved guide detached. And Fig. 9 is a sectional view corresponding substantially to the section line 9-9 of Fig. 7.

In said drawings, the machine is shown as provided with a suitable standard or frame 10 having vertically extending spaced sections 10^a-10^a between which is located a driving pulley 11 keyed or otherwise rigidly secured to a combined driving shaft and mandrel 12, the latter extending horizontally and, at its righthand end as viewed in Figure 1, providing a cylindrical mandrel proper 13 of any desired length. Mandrels of different diameter may be employed as indicated for instance by the dotted lines 13^a in Fig. 3, my invention contemplating interchangeable mandrels in which the shaft portion proper 12 may be always of the same diameter and readily removable from the driving pulley and gearing hereinafter described.

On the outer side of the frame 10, the combined mandrel and shaft 12-13 has keyed or otherwise rigidly secured thereto a driving gear 14 adapted to mesh with a pair of diametrically disposed idlers 15 and 16. Each of said idlers is specially journaled on a bracket 17 having a collar 17^a which takes over the mandrel and is adapted to be oscillated with respect to the latter to provide for adjustment. Each bracket is formed with an offset 17^b having an elongated arcuate slot 18 therein concentric with the axis of the mandrel and through which is extended a securing bolt 19 threaded into the frame of the machine so that the bracket 17 with its opening 16 or 15 may be held in any adjusted position circumferentially with respect to the mandrel within the limits contemplated.

In carrying out my invention, I use two bending or coiling rollers 20 and 21 in addition to the combined guiding and bending roller 22 supported on the standard 23 as seen in Fig. 2. Inasmuch as each of said additional coiling or bending rollers 20 and 21 is of the same form and similarly operated, it will only be necessary to detail the structure with respect to one. Referring to the roller 20, the same is provided with trunnions 24 and 25 as shown in Figure 3, the same being mounted in suitable bearings 110

formed at the top of a hollow cylindrical heavy spindle 26. Integrally or otherwise rigidly united with the trunnion 25 is a bevel or spur gear 27 meshing with a second bevel gear 28 of larger diameter, the latter being rotatably mounted about a bushing 29 formed integral with a heavy plate 30 adjustably slidably mounted on a heavy supporting bracket 31, the latter being adjustably slidably mounted on the frame 10, as hereinafter described.

The bevel gear 28, on the side opposite the bevel gear 27, meshes with another bevel or spur gear 32 carried by the end of a stud 15 shaft 33 rotatably mounted in a suitable bearing 34 carried by the slidable plate 30. At its opposite end, the stud shaft 33 is formed with a gear 35 meshing, in this instance with the idler 15. With this train of 20 gearing as best seen in Fig. 6, it will be evident that, if the mandrel were rotated in a counter-clockwise direction, as shown by the arrow *x*, the spur gear 32 will be rotated also in a counter-clockwise direction 25 as indicated by the arrow *y* which, through the intermediary of the bevel gears 28 and 27 will effect positive rotation of the roller 20, in a clockwise direction. Similarly, the roller 21 will be given a clockwise rotation 30 by means of the train of gearing associated with it.

Each bracket 31, is slidably adjustably mounted on the frame 10 so as to move in a radial direction with respect to the mandrel, this adjustment being effected by means of elongated slots 36—36, clamping bolts 37 and adjusting bolt 38. As will be evident from an inspection of Figure 2, the two brackets 31 are spaced from each 40 other circumferentially around the mandrel so as to move in lines coinciding substantially with two radii of the mandrel having an included angle of approximately 75° to 80° therebetween. With this arrangement, it is evident that each of the rollers 20 and 21 is radially adjustable with respect to the mandrel to thereby adapt the rollers for working on rods of different diameters and for coils of different diameters.

50 Each of the slide plates 30 is adjustable with respect to its respective bracket 31 and in lines parallel to the axis of the mandrel, as for instance by means of the slots 39 and clamping bolts 40. Each plate 30 is formed with opposed undercut grooves as indicated at 41—41 within which are received the edges of the bracket 31 to hold the plate 30 in assembled relation with the bracket and also to facilitate relative adjustment.

60 By referring to Figs. 3 and 5, it will be seen that the spindle 26 has secured thereto at its bottom end beneath the plate 30, a sleeve 42 which is provided with a radially extending flange-like arm 43, the latter having an elongated slot 44 therein through

which extends a clamping bolt 45 threaded into the plate 30. The spindle 26 and sleeve 42 are held rigidly together by any suitable means such as the set screw 46. With this arrangement, it is obvious that I am enabled to adjust each roller 20 and 21 angularly about an axis coinciding with a radius from the mandrel which radius extends perpendicularly to and intersects the axis of rotation of the respective roller and which also is parallel to the line of adjustment of the respective brackets 31 relatively to the mandrel.

From the preceding description, it will be seen that each of the rollers 20 and 21 is 80 positively driven in synchronism with the mandrel and preferably with a peripheral speed corresponding to the difference between the peripheral speed of the surface of the mandrel and the outside surface 85 speed of the rod or bar 47 being coiled. Also, each roller 20 and 21 is adjustable radially and axially with respect to the mandrel, as hereinbefore described. With this construction, I am enabled to always bring 90 the grooves 20^a and 21^a of the rollers 20 and 21 respectively strictly tangent to the coil being formed regardless of the pitch or diameter of the coil or diameter of the rod forming the coil and thereby obtain 95 accurate bending and coiling of the rods and true helices without deformation of the material.

Heretofore, considerable difficulty has been experienced in feeding the front end of 100 the rod or bar through the bending rollers in starting the first turn of the helix. Due to the necessity of having the rollers relatively close and of substantial and comparatively large form when working upon heavy 105 material, it is not feasible to provide a guide or deflector between the rollers and at the same time have said guide or deflector rigidly supported from the frame. To overcome the difficulty mentioned, I have provided a 110 novel guide designated generally by the reference A. Said guide is in the form of a block which, at its inner or operative end, is provided with a curved groove as indicated at 48 corresponding substantially to the 115 helix of the coil being formed but which groove 48 nevertheless is sufficiently deepened so as to leave a clearance between it and the exterior periphery of the coil as indicated at 49 in Fig. 7. With this arrangement, the guide prevents the forward end of the rod from becoming jammed between the two rollers 20 and 21 and yet does not interfere with or frictionally retard the advance of the rod during the subsequent coiling thereof. The block A is made to conform substantially to the passage defined between the two rollers 20 and 21 in alignment with the grooves thereof so that the 120 guide block has a surface 50 on each side 125 of the rollers 20 and 21 which is substantially 130

which is convex in cross section as indicated in Figure 9 and at the same time curved to conform to the periphery of the groove of the roller. As clearly shown in Figure 9, a slight amount of play or clearance as indicated at 51 is left between the guide block and the rollers so as to prevent binding while at the same time insuring the proper support and maintenance of the guide block in position by the rollers themselves without the aid of any independent supports secured to the frame of the machine.

I have herein shown and described what I now consider the preferred manner of carrying out the invention but the same is merely illustrative and I contemplate all changes and modifications that come within the scope of the claims appended hereto.

I claim:

1. In a coiling machine having a suitable frame, the combination with a mandrel; of a plurality of bending rollers disposed circumferentially around the mandrel; and independent means for adjusting each roller longitudinally of the axis of said mandrel, said means comprising a support and a roller carrying slide movably mounted upon the support.

2. In a coiling machine having a suitable frame, the combination with a mandrel; of a plurality of bending rollers disposed circumferentially around the mandrel; and means for adjusting each roller bodily rotatably about an axis coinciding with a radius from the mandrel, said adjusting means including, a roll support and an operating element connected to said roll support for moving the latter to adjust the roller about said axis.

3. In a coiling machine having a suitable frame, the combination with a mandrel; of a plurality of bending rollers disposed circumferentially around the mandrel; and means for adjusting each roller radially toward and from and axially relatively to the mandrel and independent means for adjusting each roller bodily rotatably about an axis coinciding with a radius from the mandrel.

4. In a coiling machine having a suitable frame, the combination with a mandrel; of a plurality of bending rollers disposed circumferentially around the mandrel; means for adjusting each roller axially relatively to the mandrel; means for bodily moving said adjusting means and roller radially of the mandrel; and mechanism for positively rotating each of said rollers in a direction to advance the feed of the material being coiled.

5. In a coiling machine having a suitable frame, the combination with a mandrel; of a plurality of bending rollers disposed circumferentially around the mandrel; means for adjusting each roller bodily rotatably

about an axis coinciding with a radius from the mandrel, said adjusting means including an oscillating lever; and mechanism for positively rotating each of said rollers in a direction to advance the feed of the material being coiled.

6. In a coiling machine having a suitable frame, the combination with a mandrel; of a plurality of bending rollers disposed circumferentially around the mandrel; means for adjusting each roller radially toward and from and axially relatively to the mandrel and also bodily about an axis coinciding with a radius from the mandrel, said means including a bracket adjustable toward and from the mandrel, a slide mounted on said bracket, said slide being adjustable lengthwise of the mandrel, and a roller support adjustably mounted on the slide; and mechanism for positively rotating each of said rollers in a direction to advance the feed of the material being coiled.

7. In a coiling machine having a suitable frame, the combination with a mandrel; of a plurality of bending rollers disposed circumferentially around the mandrel; means for adjusting each roller bodily rotatably about an axis coinciding with a radius from the mandrel, said means including a roller support rotatable on said frame, and a roller support operating element adjustable relative to said frame; and mechanism for positively rotating said mandrel in a direction to advance the feed of the material being coiled.

8. In a coiling machine having a suitable frame, the combination with a mandrel; of a plurality of bending rollers disposed circumferentially around the mandrel; means for adjusting each roller radially toward and from said mandrel; and means for adjusting each roller axially relatively to the mandrel; and separate means for adjusting each roller bodily rotatably about an axis coinciding with a radius from the mandrel; and mechanism for positively rotating said mandrel in a direction to advance the feed of the material being coiled.

9. In a coiling machine having a suitable frame, the combination with a mandrel; of a plurality of bending rollers disposed circumferentially around the mandrel; means for adjusting each roller axially relatively to the mandrel; mechanism for positively rotating each of said rollers in a direction to advance the feed of the material being coiled; said mechanism including a gear carried by said adjusting means and mechanism for positively rotating the mandrel in a direction to advance the feed of the material being coiled.

10. In a coiling machine having a suitable frame, the combination with a mandrel; of a plurality of bending rollers disposed circumferentially around the mandrel; means

for adjusting each roller bodily rotatably about an axis coinciding with a radius from the mandrel; mechanism for positively rotating each of said rollers in a direction to 5 advance the feed of the material being coiled; said mechanism including an element rotatable about said axis and mechanism for positively rotating the mandrel in a direction to advance the feed of the material be- 10 ing coiled.

11. In a coiling machine having a suitable frame, the combination with a mandrel; of a plurality of bending rollers disposed circumferentially around the mandrel; means 15 for adjusting each roller radially toward and from and axially relatively to the mandrel and also bodily about an axis co-inciding with a radius from the mandrel, said means including a pair of slides movable 20 at right angles to each other and a roller support rotatable on one of said slides; mechanism for positively rotating each of said rollers in a direction to advance the feed of the material being coiled; and mech- 25 anism for positively rotating the mandrel in a direction to advance the feed of the material being coiled.

12. In a coiling machine having a suitable frame, the combination with a positively ro- 30 tated mandrel; of a pair of bending rollers disposed circumferentially around the mandrel; and means for positively rotating each of said rollers, said means including, a gear rotatable in unison with the mandrel; a pair 35 of brackets oscillatably adjustable around the mandrel; a pinion carried by each of said brackets and meshing with said gear; and a train of gearing between each of said pinions and each roller.

40 13. In a coiling machine of the character

described, the combination with a mandrel; of a pair of grooved bending rollers disposed circumferentially around the mandrel; and a guide block loosely supported by and between said rollers in the grooves thereof. 45

14. In a coiling machine of the character described, the combination with a mandrel; of two grooved rollers relatively closely ad- 50 jacent and disposed circumferentially around the mandrel; and a guide block con- forming in shape substantially to the pas- sage defined by the adjacent portions of the grooves of said rollers, said block being sup- ported by and between the rollers and hav- 55 ing at its inner end an arcuate groove sub- stantially concentric with the mandrel.

15. In a coiling machine of the character described, the combination with a frame; of a mandrel; a pair of bending rollers dis- 60 posed circumferentially around the man- drel; and adjustable supporting means for each of said rollers, each of said means in- cluding a bracket slidable on the frame radially relatively toward and from 65 the mandrel, a plate slidably adjustably mounted on said bracket in a direction parallel to the axis of the man- drel, and a spindle in which the roller is di- rectly supported, said spindle being rotatably adjustable relatively to said plate about 70 an axis coinciding with a radius from said mandrel.

In witness that I claim the foregoing I have hereunto subscribed my name this 14th day of Feb., 1921.

JOHN F. O'CONNOR.
